UNITED STATES PATENT OFFICE.

WILLIAM BIRRELL, OF CHEHALIS, WASHINGTON.

SELF-RIGHTING TOY.

Application filed March 16, 1926. Serial No. 95,015.

This invention relates to wheeled toys. The object of my invention is to provide a toy of this character which is constructed in a manner to render it self-righting when turned upon its side, thus adapting it for use by little children.

In order to accomplish the object of my invention use is made in a toy of a transversely arranged member or members rigidly connected to or formed integral with the body of the toy, the outline of the outer edges of a member being formed in the semblance of a part of a wheel, and arranged with respect to the toy's center of gravity that when the toy is turned over upon one side or the other, the weight of the body will serve to return the toy into its upright position.

The invention is illustrated in the accompanying drawing, in which—

Figure 1 is a side elevation of an embodiment of my invention in a wheeled toy having the similitude of a duck; and Fig. 2 is a front elevation of the same. Fig. 3 is a side elevation of a toy wagon embodying my invention; Fig. 4 is a front elevation thereof; and Fig. 5 is a transverse vertical sectional view of the same, shown for illustrative purposes in an assumed laterally tilted position.

Referring now to Figs. 1 and 2, the reference numeral 10 represents a platform, herein shown as of an oblong rectangular shape, from the opposite sides of which extend studs 11 constituting axle journals for ground wheels 12, two at each side. Rigidly secured to said platform centrally of its width is a longitudinally disposed body member 13 having the configuration of a duck, although it may be the representation of any other bird, an animal, fish, etc. Mounted rigidly upon the platform 10, at each side of the body member 13, is a wing member 14 which, in the illustrated embodiment, is shown as disposed at right angles to the plane of said body member.

Said platform, body and wing members constitute an integral or unitary structure. Said wing members have their outer lateral edges 15 of a curved shape, preferably arcs of a circle or the periphery of a cylinder which if produced, as indicated by dotted lines 16 in Fig. 2, is adapted to encompass a space containing the ground wheels 12.

The axis A of the arcs of said wings, and of the projected cylinder above referred to,

is positioned in a central longitudinal vertical plane of the toy, and above the center of gravity G of the entire toy when the latter is in its normal or upright position; 60 that is to say, with all of its ground-wheels bearing upon a substantially horizontal floor or other support.

By thus having the axis of the arcuate outer edges 15 of both wings disposed normally above the center of gravity of the toy, it is apparent that gravitation will act to cause the toy to roll upon a wing edge 15 back into such normal upright position, in the event of the toy being turned over in 70 one lateral direction or the other, thereby affording a self righting toy.

In the embodiment shown in Figs. 3 to 5, inclusive, I show a wagon-box structure 20 having axles 21 upon which are journaled 65 the ground-wheels 22. In this construction the wagon box is provided with end members 23 each having the shape of a segment of a circle, the chord of which corresponds with the box bottom wall 24. 80

The end walls 23 have the arcuate parts 25 of their peripheries correspond with the peripheral surface of a projected cylinder whose axis is indicated by A¹.

Such projected surface, if extended, as 85 represented by dotted line 27 in Fig. 5, encompasses the ground-wheels 22. The center of gravity, indicated by G¹ in Figs. 4 and 5, of the toy wagon as a whole, is located below and in a vertical plane which extends 90 through the axis A¹ when the wagon is in its normal upright position as represented in Fig. 4.

By positioning the axis A¹ of the arcuate edge portions of the end walls 23 above the 95 center of gravity of the wagon as a whole, the power of gravitation serves to roll the wagon laterally from any tipped over position back into its normal upright position. 100

This self righting characteristic of the invention will be understood from an inspection of Fig. 5, wherein let a line a be extended radially of the axis A¹ and vertically of the floor or support for the toy; and a vertical line g, indicating the force of gravitation acting downwardly through the center of gravity G¹ forms, with the reactionary force applied upwardly at line a, a couple of revolutions which will serve to roll the wagon back into the upright position in 110 which it is represented in Fig. 4.

From the foregoing, it will be apparent

that the pair of wings 14 of the first described toy (Figs. 1 and 2) and the end walls 23 of the other described toy (Figs. 3 and 4) with their arcuate outer edges will, 5 in effect, function as wheels whereby the power of gravitation will serve to roll the respective toy from a turned over position back into its normal upright position.

A toy constructed according to my invention 10 may be propelled by any suitable means as, for example, by being pushed, or by being pulled through the instrumentality of a cord (not shown) connected, for instance, to an eye attachment 29 provided for that 15 purpose at the front end of a toy.

The construction and principles of operation of my invention will be readily apparent from the foregoing description. While I have described two embodiments of

my invention, I desire to have it understood 20 that they are merely illustrative and that changes may be made, if desired, within the scope of the appended claim.

What I claim, is,—

A self-righting toy comprising a structure 25 mounted upon ground-wheels, said structure being provided with members arranged transversely of the longitudinal axis of the toy, the outer edges of said members being of circular arcuate form which produced 30 will encompass the space containing said ground-wheels, the axis of generation of the arcuate edges of said members being located normally above the center of gravity of the toy.

Signed at Chehalis, Washington, this 13th day of January, 1926.

WILLIAM BIRRELL.
